CLAIM

The ornamental design for a duct with an indented end, as shown and described.

DESCRIPTION

FIG. 1 is a front elevational view of a first embodiment of a duct with an indented end; the right, left and rear elevational views being identical to FIG. 1;

FIG. 2 is a top view of the duct of FIG. 1;

FIG. 3 is a front right perspective view of the duct of FIG. 1; the front left perspective view being a mirror image of FIG. 3;

FIG. 4 is a front elevational view of a second embodiment of a duct with an indented end; the right, left and rear elevational views being identical to FIG. 4;

FIG. 5 is a top view of the duct of FIG. 4; and,

FIG. 6 is a front right perspective view of the duct of FIG. 4; the front left perspective view being a mirror image of FIG. 6.

The broken lines shown in FIGS. 2, 3, 5 and 6 are for illustrative purposes only and form no part of the claimed design.
